SOLVENT EXTRACTION OF HYDROCARBON MATERIALS

Robert W. Henry, Bartlesville, and James V. Montgomery, Okmulgee, Okla., assignors to Phillips Petroleum Company, a corporation of Delaware

Application March 25, 1940, Serial No. 325,843

4 Claims. (Cl. 196—13)

This invention relates to the refining of mineral oils, and more particularly to the refining of mineral oils by solvent extraction.

In some processes single solvents are used for contacting the oil undergoing refining and removing by simple solution or extraction the undesirable constituents from the paraffinic constituents of the oil. It was found that yields of the finished oils were increased by use of refrigeration. Another improvement was made wherein the solubilities of the various types of hydrocarbons were preferentially altered by the addition of a second constituent to the solvent. This operation greatly increased the flexibility of the process as well as improving the quality of the finished oil.

The use of water as a solvent modifying agent has been suggested and when used in systems in which water was at least partially soluble in the solvent, reasonably good yields of superior quality oils resulted.

In these above mentioned processes, the undesirable constituents, such as naphthenic and asphaltic hydrocarbons, are removed or extracted from the oil phase by contact with the solvent phase. The use of refrigeration increases the yields of finished paraffinic oils by reducing the amount of paraffinic constituents held in solution in the solvent phase. The refrigeration may be carried out in the original extraction apparatus or may be applied subsequently. In either event the use of refrigeration is an expensive operation. It is the purpose of this invention to develop a process of solvent extraction in which the maximum yield of highest quality finished oil is obtained without the use of refrigeration or any appreciable cooling. At the same time, the process is most flexible and may be adapted to treatment of stocks produced from crude or other oils from any source.

To obtain this maximum yield of oil or raffinate phase having the most desirable properties, that is, most nearly free from naphthenic or asphaltic constituents, it was necessary to find a selective solvent which will dissolve the entire body of oil which is to be treated. Upon the addition of a solubility modifier such as water, the relative solubility of the hydrocarbon constituents is greatly altered. When a properly controlled amount of such solubility modifier is added, essentially complete precipitation of desirable paraffinic materials into a raffinate phase is accomplished without the assistance of refrigeration or other intended cooling. Other solubility modifying agents such as certain of the lower molec-

ular weight iso-alcohols, or liquefied normally gaseous hydrocarbons, may be used, but due to the normal mode of operation of these more common processes, maximum results are not obtained. Most of the solvent processes prefer to secure only partial miscibility of the oil and solvent, which process results in partial or imperfect contact between solvent and oil. Some processes employ high temperatures to effect complete solution of the oil in the solvent in an attempt to take advantage of the more nearly perfect extraction gained therethrough. Those commercial processes which utilize solvents completely miscible with the oils at atmospheric temperatures are forced to perform the separation step at low temperatures, requiring refrigeration. Improved efficiencies are attained in these processes utilizing complete miscibility but only at the price of high operating costs.

20 We have found it possible to obtain the advantage of complete miscibility of oil and solvent and yet secure efficient separation of phases all at one convenient temperature.

It is an object of this invention to develop a process in which ultimate or essentially molecular contact between the oil and the solvent is attained.

Another object is to obtain complete miscibility between the solvent and oil at essentially atmospheric temperature.

30 Another object is to effect separation of the oil-solvent solution into phases by means other than changes in temperature.

Another object is to develop a process which readily adapts itself to continuous as well as to batch or intermittent operation.

Another object is to develop a process in which raffinate fractions of uniformly changing properties may be separated.

40 Still another object is to produce a flexible process in which essentially any type of oil can be separated into its paraffinic and less desirable constituents.

Other objects and advantages of the invention will be apparent during the course of the following description.

In the process of solvent extraction of mineral oils, it is recognized that there are distinct advantages in first securing complete miscibility between the solvent and oil and then causing a separation of the raffinate and extract phases, in that the ultimate contact of the oil with the solvent is thus secured with consequent improvement of efficiency. We have found it practical 55 to obtain the advantages of complete miscibility

and yet to secure convenient separation of phases, all at one convenient temperature when using a water-soluble or partially water-soluble solvent. We first mix the oil to be extracted with a solvent in which the oil is entirely soluble, in such a way that the oil completely, or substantially completely dissolves in said solvent. In this solution stage ultimate contact between oil and solvent is then secured. A suitable solvent consists in heterocyclic nitrogen bases of the pyridine type, their water-soluble homologues or derivatives. The solvent is so selected and partially or completely purified as to be miscible in all proportions with the oil at ordinary atmospheric temperatures. A solvent composition which meets these requirements is composed of a selected fraction of commercial pyridine boiling between 260°-320° F. and to which is added 1.25 per cent water, by volume. This prepared solvent and an unextracted oil are completely miscible at a convenient operating temperature, say 90° F., and thus ultimate contact of oil and solvent is secured without recourse to elevated temperatures.

After this above mentioned solution of oil in solvent has been effected, the solution is then mixed with such an amount of water, or similar low miscibility liquid such as a lower aliphatic alcohol, in a second step so as to cause partial miscibility of the solvent with the oil and consequent separation of a raffinate from an extract phase. The relative volume of raffinate phase which separates from the solution is dependent upon the amount of low miscibility liquid added. The raffinate phase is separated from the extract phase, and each is freed of solvent separately by any known method, as by distillation or by absorption or by washing of the solvent from the oil. The extract phase from the above described extraction may be admixed with additional water, or similar low miscibility liquid, so as to cause separation of a second raffinate phase of essentially any desired volume. This stepwise addition of water or the like and the separation of the resulting phases may be repeated as often as desired, and each final phase product freed of solvent as above.

The figure illustrates one apparatus in which the process may be carried out, but it is not intended to limit the operation of this invention to the use of this particular type of apparatus.

Referring to the diagram, tanks 1 and 3 are run or storage tanks for untreated oil and solvent, respectively. 2 is a conventional mixing apparatus; tanks A, B, C and D are settlers or separators; 8, 13, 18 and 23 represent stills. 26 represents a still fitted with a fractionating column which in turn is equipped with at least one side-draw. Pumps, lines, valves, regulators, etc. are supplied as required.

The following discloses the operation of the process as applied to the solvent extraction of a Mid-Continent residual bright stock. The operation of the process for the refining of this bright stock is given merely as one example and the process is not intended to be limited to the refining of this type of stock. Stocks such as residuals, overhead, cylinder stocks, etc., arising from essentially any type of mineral or other oil from essentially any locality may be solvent extracted according to the process herein disclosed or by relatively simple alteration therein.

The residual stock is pumped at the rate of 1,000 barrels per day from storage tank 1 into the mixing apparatus 2 in which the oil is mixed

with solvent from storage tank 3 in the proportion of one volume of oil to three volumes of solvent. This solvent comprises the fraction of commercial pyridine boiling from 260°-320° F. to which has been added 1.25 per cent water by volume. The oil and solvent are completely miscible at the operating temperature of 90° F. and by such operation ultimate contact of oil and solvent is secured without recourse to elevated temperature.

10 The solution of oil and solvent is transferred through line 4 to pump 5 and thence into separator A at the rate of 4,000 barrels per day. A sufficient quantity of constant boiling mixture of pyridine fraction and water (consisting of approximately 40% water and 60% pyridine fraction) is added from line 6 to increase the water content of the solvent in separator A. At the convenient operating temperature this concentration of water in the solvent is sufficient to cause the separation of a raffinate phase which is then removed through line 7 to still 8 for separation into raffinate oil and solvent. The former (raffinate) passes to storage through line R₁, while the solvent is returned to tank 3 for reuse.

15 The extract phase is transferred from separator A through line 9 and pump 10 into separator B. A sufficient quantity of constant boiling solvent mixture is added from line 11 to cause in 20 separator B the separation of a second raffinate phase which is in turn separated into raffinate No. 2 and solvent by fractionating in still 13. The raffinate passes to storage through line R₂ and the solvent is returned to tank 3 for recycling.

25 The extract phase remaining in separator B is transferred through line 14 and pump 15 into separator C and during this transfer additional constant boiling mixture from line 16 is added. 30 In separator C, due to the increased water content of the solvent, a third raffinate phase separates, and it in turn is withdrawn through line 17 to still 18 in which it is separated into oil, called raffinate No. 3 and solvent. The oil passes to storage through line R₃ and the solvent is returned to tank 3 for recycling.

35 The extract phase remaining in separator C is then transferred through line 19 and pump 20 along with additional constant boiling solvent mixture from line 21, to separator D. In 40 this settler another raffinate phase separates and is withdrawn through line 22 to still 23 in which the oil, labelled raffinate No. 4 and thereafter transferred to storage through line R₄, is separated from the solvent. The latter is transferred to tank 3 for reuse.

45 The final extract phase is transferred from separator D through line 24 and pump 25 into still 26. This still is equipped with a fractionating column and means of creating and controlling reflux. The overhead distillate from still 26 is composed of a constant boiling mixture of the solvent and water. This mixture is stored in the run tank 29 from which it is transferred by pump 27 through line 28, and lines 6, 11, 16 and 21 for reuse in the several separators. The sidestream from still 26 is composed of solvent containing a low percentage of water, less than 1.25 per cent, and it is returned through pump 31 and line 30 to the storage tank 3. The residue from still 26 consisting of extract oil, is transferred to extract storage.

Example

50 A Mid-Continent residual bright stock when

solvent treated in the apparatus and by the process herein described gave the following results. The particular operating conditions and solution concentrations were: 1000 barrels per day of bright stock was mixed with solvent in the mixing apparatus in the proportion of one volume of oil to three volumes of solvent. This solvent comprises the pyridine fraction boiling from 260°-320° F. to which was added 1.25 per cent water by volume. The mixer temperature was 90° F. While transferring the solution of oil and solvent to the separator A, sufficient constant boiling mixture (consisting of approximately 40% water and 60% pyridine fraction), was added to increase the water content of the solvent to 2 per cent by volume. From this solution a raffinate phase separated which contained 45 per cent oil and 55 per cent solvent. This solvent contained 1.4 per cent water by volume. The solvent was removed from the raffinate phase and returned to run storage while the raffinate No. 1 oil comprising 20 per cent of the original stock, or 200 barrels per day, was pumped to storage.

To the extract phase from separator A was added sufficient constant boiling mixture (consisting of approximately 40% water and 60% pyridine fraction) from tank 29 to increase the water content of the solvent in separator B to 2.35 per cent. A raffinate phase separated, which contained 47 per cent of a paraffinic oil and 53 per cent solvent. This solvent contained 1.6 per cent water by volume. The raffinate oil was marked raffinate No. 2 and comprised 20 per cent by volume of the charge stock, or 200 barrels per day.

The extract phase from raffinate No. 2 in separator B was transferred to separator C and sufficient constant boiling mixture (consisting of approximately 40% water and 60% pyridine fraction) added during transit to bring the water content of the solvent in separator C to 2.85 per cent by volume. A raffinate phase containing 52 per cent paraffinic oil and 48 per cent solvent separated in C. This solvent contained 1.8 per cent water. After separation from the solvent this raffinate, labelled raffinate No. 3 comprised 20 per cent by volume of the original stock, or 200 barrels per day.

The extract from raffinate No. 3 was transferred from separator C to separator D with the addition of sufficient constant boiling mixture (consisting of approximately 40% water and 60% pyridine fraction) to bring the water content of the solvent in the latter to 4.1 per cent by volume. A raffinate phase containing 67 per cent paraffinic oil and 33 per cent solvent separated. This solvent contained 1.8 per cent water. The raffinate oil was separated from the solvent, labelled raffinate No. 4 and transferred to storage. It comprised 20 per cent by volume of the charge stock, or 200 barrels per day.

The final extract from raffinate No. 4 in separator D was fractionated in still 26 into an extract oil bottoms, a solvent side cut and a solvent overhead. This side cut solvent contained a low percentage of water, less than 1.25 per cent by volume while the overhead was a constant boiling mixture of water and nitrogen base, both fractions were continuously recycled. The extract was pumped to storage.

In this example it is evident that the ratio of solvent to oil increased in each successive separator because of the fact that the solvent to oil ratio in the raffinate phase withdrawn from each

separator was much less than the original 3:1 mixture. The solvent to oil ratios were: 3:1 in A, 3.5:1 in B, 4.4:1 in C, and 6.2:1 in D. This increased ratio of solvent to oil, tended to assist in holding naphthenic materials in solution and thus to produce raffinates of good quality from each separation. The percentage of oil dissolved in the solvent of the extract phase decreased from about 22 per cent from separator A to about 7.8 per cent of oil from that of separator D. The selectivity of the solvent increases as the concentration of dissolved oil decreases, and thus good selectivity between paraffinic and naphthenic oil was obtained.

20	Charge	Tests on the charge oil and fractions were:				
		Raffinate fractions				Extract
		No. 1	No. 2	No. 3	No. 4	
25	Volume (per cent)	100	20	20	20	20
	Gravity, A. P. I.	24.0	25.4	25.0	24.8	24.0
	Viscosity, Saybolt universal 210° F. seconds	156.3	167.8	163	155.1	134.8
	Viscosity index	80	90	88	87	82
						177.8
						43.5

30 From these data, it is evident that raffinate No. 1 consisted of a high quality paraffinic oil of higher viscosity than the charge stock, and was an excellent bright stock. Raffinates 2, 3 and 4 decreased in quality successively, but in all cases were improved over the original charge. The extract was a dark viscous oil of low viscosity index and contained resinous and naphthenic material.

It is to be understood that while the constant boiling point mixture of pyridine and water has been described as to the precipitant, it has been found the low boiling alcohols such as methyl, ethyl, propyl and iso-propyl or mixtures of water and low boiling alcohols are effective precipitants in similar manner.

45 It should be realized that the process herein described is sufficiently flexible as to cover a wide range of operation. Practically any mineral or other oil may be charged and any desired number of fractions obtained therefrom. A treated oil may be separated into cuts of varying paraffinicity, as shown in the above given example or an untreated cylinder stock may be separated into fractions consisting of tar, resins, naphthenic oil, and paraffinic oil, in which case the extract would contain the tar fraction.

50 We have shown the separators to be simple vertical settlers. They may be horizontal if desired. Each separation may be improved by counter current washing, reflux of extract, etc., in conventional manner, although such improvements are not as necessary in our process as in conventional solvent extraction since we obtain complete miscibility of oil and solvent prior to each separation.

We claim:

65 1. The method of refining and purifying mineral oil to separate the asphaltic and other undesirable bodies from the relatively more desirable paraffinic portion of the oil including the steps of mixing the mineral oil with a water soluble solvent comprising a commercial pyridine fraction boiling between 260° F. to 320° F., to form substantially one homogeneous solution, adding to the solution a constant boiling point mixture of water in a fraction of commercial pyridine 70 boiling between 260° F. to 320° F. as a precipitant

to separate the solution into a desirable raffinate phase and a less desirable extract phase, separating the two phases, adding to the extract phase additional constant boiling point mixture of water in a fraction of commercial pyridine boiling between 260° F. to 320° F. as a precipitant to separate the extract into a second raffinate phase and a second extract phase, again separating the two phases and then separating from the second extract phase previously added solvent and previously added constant boiling point precipitant in one operation.

2. The method of refining and purifying mineral oil to separate the asphaltic and other undesirable bodies from the relatively more desirable paraffinic portion of the oil including the steps of mixing the mineral oil with a water soluble solvent comprising a commercial pyridine fraction boiling between 260° F. to 320° F., to form substantially one homogeneous solution, adding to the solution a constant boiling point mixture of water in a fraction of commercial pyridine boiling between 260° F. to 320° F. as a precipitant to separate the solution into a desirable raffinate phase and a less desirable extract phase, separating the two phases, adding to the extract phase additional constant boiling point mixture of water in a fraction of commercial pyridine boiling between 260° F. to 320° F. as a precipitant to separate the extract into a second raffinate phase and a second extract phase, again separating the two phases, then separating from the second extract phase previously added solvent and previously added constant boiling point precipitant in one operation and recycling the solvent and precipitant.

3. The method of refining and purifying mineral oil to separate the asphaltic and other undesirable bodies from the relatively more desirable paraffinic portion of the oil which comprises mixing the mineral oil with a water soluble solvent comprising a fraction of commercial pyridine boiling between 260°-320° F. to form substan-

tially one homogeneous solution, adding to the solution as a precipitant a constant boiling point mixture of water in a fraction of commercial pyridine boiling between 260°-320° F. to separate the solution into a desirable raffinate phase and a less desirable extract phase, and controlling the precipitation by controlling the amount of the said constant boiling point mixture added, separating the two phases, adding to the extract phase an additional controlled amount of said constant boiling point mixture to separate the extract phase into a second raffinate phase and a second extract phase, again separating the two phases, then separating from the second extract phase previously added solvent and previously added constant boiling point mixture in one operation.

4. The method of refining and purifying mineral oil to separate the asphaltic and other undesirable bodies from the relatively more desirable paraffinic portion of the oil which comprises mixing the mineral oil with a water soluble solvent comprising a fraction of commercial pyridine boiling between 260°-320° F., to form substantially one homogeneous solution, adding to the solution as a precipitant a constant boiling point mixture of water in a fraction of commercial pyridine boiling between 260°-320° F. to separate the solution into a desirable raffinate phase and a less desirable extract phase, and controlling the precipitation by controlling the amount of the said constant boiling point mixture added, separating the two phases, adding to the extract phase an additional controlled amount of said constant boiling point mixture to separate the extract phase into a second raffinate phase and a second extract phase, again separating the two phases, then separating from the second extract phase previously added solvent and previously added constant boiling point mixture in one operation and recycling the solvent and constant boiling point mixture.
